UNITED STATES PATENT OFFICE.

WILLIAM C. MAYNARD, OF CANTON, OHIO.

DESIGN FOR A MEAT-CHOPPER.

SPECIFICATION forming part of Design No. 24,482, dated July 16, 1895.

Application filed June 10, 1895. Serial No. 552,343. Term of patent 14 years.

To all whom it may concern:

Be it known that I, WILLIAM C. MAYNARD, a citizen of the United States, and a resident of Canton, county of Stark, State of Ohio, have 5 invented and produced a new and useful Design for Meat-Choppers, of which the following is a full, clear, and exact description, reference being had to the accompanying drawing, making part of this specification.

10 My invention relates to a design for meat-choppers.

In the accompanying drawing I have illustrated the design in perspective.

15 My design consists of and the leading features are a circular cutter A, the handle-frame,

the base B, curved to coincide with the circle described by the cutter, converging arms D, curved transverse the base and extended upward and over to a point about central to the circle of the cutter and united to form a 20 handle-support E, and a handle F.

What I claim is—

The design for a meat chopper, substantially as set forth.

In testimony whereof I have hereunto set 25 my hand this 30th day of May, A. D. 1895.

WILLIAM C. MAYNARD.
